UNITED STATES PATENT OFFICE

LEWIS T. WILCOX, OF PEEKSKILL, NEW YORK

WATER HEATER

Application filed June 28, 1927. Serial No. 201,996.

This invention relates to water heaters of the auxiliary type wherein water is circulated through a single or multiple helical coil, the coil being supported over a burner which heats the exterior of the coil. The burners are usually of the liquid or vapor fuel burning type, though any type burner may be used. A casing usually surrounds the heating coil and the major portion of the burner, which casing may be connected to a flue pipe to carry off the hot gases after they have served to heat the coils. Heaters of this type when connected to a flue pipe and in operation are usually accompanied by a roaring noise due to the extra induced draught and rush of hot gases up the casing and flue pipe, since the heaters are designed to operate without a flue pipe connection.

It is the purpose of this invention to eliminate this roaring noise and at the same time to obtain a more efficient utilization of the heat generated by the burner and to prolong the life of the heater whether the heater has a flue connection or is operated without such a connection.

It is also an object of this invention to provide a more satisfactory supply reservoir from which the burner receives its fuel in those types of burners which burn liquid fuel.

It is also an object of this invention to provide a hinge pin which engages both hinges on one side of the casing and which may be partially removed by a single means to disengage one pair of hinges.

In accordance with my invention I provide a sheet or cast metal casing for the heater which may conveniently be formed of two vertical sections adapted to be hinged upon either side as shown and described in my copending application Serial No. 148,648. At the upper end of this casing I propose to form the casing with a restricted opening to retard the flow of hot gases arising therefrom and thereby obtain a more efficient and complete utilization of their heat. In cooperation with this restriction I propose to provide a means for permitting the entry of air from the exterior into the flue pipe at the point where the hot gases leave the casing

and enter into the flue pipe. In this manner, by restricting the flow and injecting air into the flue pipe I not only obtain more efficient utilization of the heat of the hot gases and eliminate the roaring noises usually accompanied with the operation of a water heater, and eliminate the sucking out of the flame but also dilute the hot gases in the flue pipe thereby obtaining a cooler mixture in the flue pipe which will substantially reduce fire hazard and prolong the life of the flue pipe.

As a means insuring a better fuel supply, I propose to form the bottom of the reservoir tank with a depressed portion to which is connected a well or chamber to collect water and other foreign matter and to the higher portion of the bottom I make the fuel connection leading to the burner.

In order to provide a convenient hinge and catch for the casing I provide a connection between pins engaging the two pairs of hinges on each side of the casing which serves as a handle whereby the hinges upon either side may be disengaged at will to allow the casing to be opened by swinging upon the other set of hinges.

I will now give a more detailed description of a heater constructed in accordance with this invention in connection with the drawings, in which:

Fig. 1 is a front elevation partly in section of a water heater and supply tank constructed in accordance with my invention.

Fig. 2 is a section on line 2—2 of Fig. 1;

Fig. 3 is a vertical section through the upper end of the heater casing and flue connection;

Fig. 4 is a plan view of the heater casing;

Fig. 5 is a detail section on line 5—5 of Fig. 3;

Fig. 6 is a vertical section through the upper portion of a modified casing;

Fig. 7 is a section on line 7—7 of Fig. 6, and

Fig. 8 is a detail section of the sediment bulb and drain plug.

In the embodiment shown in Figs. 1 to 5 inclusive, I utilize a vertically split sheet metal casing comprising a front section 1 and a rear section 2 somewhat similar to that shown and described in my copending appli-

cation Serial No. 148,648. The upper end of the casing differs, however, and is formed with an inturned flange 3 which forms a reduced opening at the upper end of the casing. To this flange there is secured a circular connecting collar 4 of larger diameter at the bottom than at the top and which has four projections or feet 5 on the lower end; three of which feet are secured to the rear half of the casing, while the fourth foot rests over the front section 1 and is left free thus enabling the front part of the casing to be swung on its hinges without interference. These feet resting upon flange 3 support the collar above the casing leaving spaces therebetween through which air may be sucked up and into the flue. The collar 4 extends upwardly and terminates in a vertical flange 4^a of proper diameter to fit within the end of a flue pipe 6 of substantially larger diameter than the opening in the upper end of the casing. This flange will guide the hot gases upwardly and into the flue pipe and prevent their escape outwardly between the feet of the collar.

Thus by reducing the diameter of the opening at the top of the casing and thereby reducing the rapidity of flow of hot gases through the casing, and by providing means for causing the injection of air from the exterior into the flue pipe I not only substantially eliminate all roaring noises but obtain a more complete absorption of heat from the hot gases into the water within the heating coils and thus provide a more efficient heater.

The restricted opening at the top of the casing in conjunction with the openings permitting air to be sucked into the flue from the exterior maintains the draught through the casing constant and of the proper magnitude regardless of the flue connection. If a greater draught is caused by the connection more air will be sucked in through the openings, since the restricted opening in the casing will tend to maintain a constant draught therein.

As one practical way of securing the connecting collar 4 to the top of the casing, I form slots in the inturned flange 3 of the rear half 2 of the casing, properly spaced and positioned so as to be directly opposite the three rear feet formed on collar 4. The front half of the casing is formed with two diametrically opposite lugs 7 projecting rearwardly from the rear edge of flange 3 and so placed that when the casing is closed the lugs will be immediately adjacent to the two slots in the front edges of the flange 3 on the rear section 2. The legs 5 of the collar are tapped to receive screws 8 or the like which are inserted in the legs but not screwed tightly therein before the collar is placed on top of the casing. With the screws extending from the feet the collar 4 may be slid over the top flange 3, with the screws 8 engaged in the slots, after which the front section 1 of the casing may be closed, whereby lugs 7 projecting from the front sec-

tion 1 of the casing will engage the feet and push them rearwardly in the slots. The screw may then be tightened and the collar will be permanently and rigidly held to the rear section of the casing in a manner to permit opening of the front section. 70

In Figs. 6 and 7 I have shown a modified form of a sectional casing comprising a front section 1^a and a rear section 2^a, and a modified form of connection collar. In this type the top of the casing is formed with an inturned flange 9 as before, resulting in a restricted opening in the top of the casing. The top of the casing is also formed with upstanding lugs 10 having laterally extending and slotted webs 11 to which a circular collar 12 may be attached. Collar 12 is substantially the same as collar 4, being tubular and of greater diameter at the bottom than at the top and terminating at its upper end in a vertical flange 13 adapted to slide into a flue pipe 14 of larger diameter than the opening in the upper end of the casing. The collar 12 is secured to the casing by means of bolts 15 inserted through apertures in the collar and engaging in the slots in webs 11. As an additional security against the collar 12 sliding laterally the collar is formed with a lug 16 projecting downwardly from the inner surface of the collar so as to engage the inner surface of the rear lug 16 and maintain the collar well up in the slots in the webs 11. 80 85 90 95

Here, as before, due to the injection action, air will be drawn in from under the collar and between the projections on top of the casing and into the flue pipe resulting in the advantages previously pointed out.

To insure a continuous supply of liquid fuel free from water and other foreign matter I have found it advantageous to employ the usual inverted bottle feed and to form the subtank 16 of the usual inverted bottle type reservoir with a depressed portion 17. A well or sediment bulb 18 is attached to the periphery of an aperture in this depressed portion and provided with a drain plug 19. It has been found desirable to construct the drain plug 19 in a manner which will permit draining of the subtank 16 without soiling the fingers. To this end the plug 19 is provided with a longitudinal bore 20 terminating in a transverse bore 21 adjacent the upper end of plug 19. An annular groove is turned in the plug communicating with the ends of transverse bore 21. The inner end of plug 19 is tapered to seat within the corresponding tapered seat portion of a gland 22 into which the plug 19 is threaded and which is secured to the bottom of bulb 18. It follows, therefore, that if plug 19 is withdrawn slightly from gland 22 the liquid in bulb 18 will flow through the annular groove 21 and outwardly through the center of plug 19 whereby it is not necessary to soil the fingers when the bulb is drained. To the higher portion of the 100 105 110 115 120 125 130

bottom I attach the usual subtank elbow 23 which in turn is connected to the supply pipe 24 feeding the burner 25. It is obvious that water or other foreign materials will settle 5 to the lower portion 17 of the bottom of sub-tank 16 and in sediment bulb 18 from which it may be drained at certain intervals. The 10 elbow 23, being connected to the high portion of the bottom, will receive only the clear fuel oil.

As heretofore mentioned the casing is constructed of two sections hinged upon both sides. Accordingly the two sections 1 and 15 26 substantially at the top and bottom of each side of the casing.

A single hinge pin 27 is provided for both 20 pairs of hinge elements upon one side of the casing. This pin 27 comprises a long rod bent at right angles intermediate its ends to 25 form an offset parallel portion 28 which serves as a handle. One end of the pin is also bent to form an offset parallel end as at 29 while the other end is offset and bent double or back upon itself as at 30 thus causing 35 both ends of the pins to enter the hinge elements simultaneously and from the same relative directions. The offset is sufficient to permit the ends of the pin to extend through the hinge elements while the main portion of 30 the pin lies adjacent the casing. A clamp 31 is attached to the casing and surrounds the pin shortly above the upper horizontal arm of the handle and thereby limits the vertical 35 movement of the pin to a proper amount to disengage the lower hinge element of each pair.

It is apparent that one pin need only be 40 raised a slight amount till the ends thereof are free from one each of the hinge elements to enable the front section of the casing to be swung open upon the opposite pin as a hinge and that the casing may be opened from either side by merely raising the necessary pin a short distance.

When in operation the hot gases generated 45 from the burner will rise through the casing, but instead of passing directly and uninterruptedly therethrough and into the flue pipe 50 the gases will be hindered in their ascent and restricted by the reduced opening in the top of the casing from which they will pass upwardly in a column of reduced diameter 55 into the flue pipe. As this column of hot gases of reduced diameter passes into the flue there will be a strong injection action whereby 60 cool air will be drawn in from the sides of the casing and mixed with the rising hot gases. This action will substantially eliminate 65 the roaring noise as well as cool the flue gases and thereby prolong the life of the flue pipe. The hot gases will also be retained in the casing for a longer period and will give up a greater amount of their heat to the coils

therein, thus resulting in a more efficient heater.

It is apparent that many variations may be made in the design of the minor details without departing from the spirit and scope of 70 this invention as defined in the appended claims.

I claim:

1. A water heater including a burner, a heating coil disposed thereover, a sectional casing surrounding said coil and having a flue opening in the upper end thereof, one of said sections being slotted at its upper end and the other section having a cooperating lug extending therefrom, a tubular collar having its upper end terminating in a flange adapted to engage a flue pipe and its lower end terminating in a plurality of feet, and means for securing certain of said feet to said casing comprising screws extending 75 through said slots and into certain of said feet.

2. A water heater including a burner, a heating coil disposed thereover, a split casing surrounding said coil comprising two vertical sections having a pair of hinge elements at the top and bottom on opposite sides thereof and a single hinge pin for each side of said casing extending through both pairs of hinge elements. 85

3. A water heater including a burner, a heating coil disposed thereover, a split casing surrounding said coil comprising two vertical sections having a pair of hinge elements at the top and bottom on opposite sides thereof and a single hinge pin for each side of said casing extending through both pairs of hinge elements, each of said pins being bent to form a handle intermediate its ends. 100

4. A water heater including a burner, a heating coil disposed thereover, a split casing surrounding said coil comprising two vertical sections having a pair of hinge elements at the top and bottom on opposite sides thereof and a single hinge pin for each side of said casing extending through both pairs of hinge elements, one end of each of said pins being bent back upon itself whereby said pins may be partially withdrawn to release 110 said hinge elements. 115

5. A water heater including a burner, a heating coil disposed thereover, a split casing surrounding said coil comprising two vertical sections having a pair of hinge elements at the top and bottom on opposite sides thereof and a single hinge pin for each side of said casing extending through both pairs of hinge elements, one end of each of said pins being bent back upon itself whereby said pins enter said hinge elements from the same relative sides simultaneously, and means for limiting movement of said pins. 125

6. A water heater including a burner, a heating coil disposed thereover, a split casing 130

surrounding said coil comprising two vertical sections having a pair of hinge elements at the top and bottom on opposite sides thereof and a single hinge pin for each side of said casing extending through both pairs of hinge elements, one end of each of said pins being bent back upon itself whereby said pins enter said hinge elements from the same relative sides simultaneously, and means for limiting movement of said pins comprising stops secured to said casing and engaging said pins.

7. A water heater including a burner, a heating coil disposed thereover, a split casing surrounding said coil comprising two vertical sections having a pair of hinge elements at the top and bottom on opposite sides thereof and a single hinge pin for each side of said casing extending through both pairs of hinge elements, each of said pins being bent to form a handle portion intermediate its ends, one end of each of said pins being bent back upon itself whereby said pins enter said hinge elements from the same relative sides simultaneously and means for limiting movement of said pins comprising stops secured to said casing and engaging said pins adjacent the handle portions thereof.

In witness whereof, I hereunto subscribe my signature.
